US00D995247S

(12) **United States Design Patent** (10) **Patent No.:** **US D995,247 S**
(45) **Date of Patent:** **** Aug. 15, 2023**

(54) **SOLDERING IRON**

(71) Applicant: **GUILBERT EXPRESS,**
Fontenay-sous-Bois (FR)

(72) Inventor: **Yves Guillou**, Brou-sur-Chantereine
(FR)

(**) Term: **15 Years**

(21) Appl. No.: **35/512,817**

(22) Filed: **Jul. 30, 2021**

(80) **Hague Agreement Data**

Int. Filing Date: **Jul. 30, 2021**

Int. Reg. No.: **DM/216867**

Int. Reg. Date: **Jul. 30, 2021**

Int. Reg. Pub. Date: **Oct. 29, 2021**

(51) **LOC (14) Cl.** **08-05**

(52) **U.S. Cl.**

USPC **D8/30**

Primary Examiner — Rachel A. Voorhies

Assistant Examiner — Benjamin D. Wannemacher

(57) **CLAIM**

The ornamental design for soldering iron, as shown and described.

DESCRIPTION

1. Soldering iron

1.1: Perspective

1.2 : Front

1.3 : Back

1.4 : Right

1.5 : Left

1.6 : Top

1.7 : Bottom

The features of the soldering iron shown in broken lines
form no part of the claimed design.

1 Claim, 7 Drawing Sheets
